UNITED STATES PATENT OFFICE.

JOHN RIOS, OF NEW YORK, N. Y.

THERMOSTATIC SWITCH.

1,350,183.

Specification of Letters Patent. Patented Aug. 17, 1920.

Application filed October 22, 1918. Serial No. 259,169.

To all whom it may concern:

Be it known that I, JOHN RIOS, a citizen of the United States of America, residing at New York, in the county of New York and State of New York, have invented new and useful Improvements in Thermostatic Switches, of which the following is a specification.

As its principal purpose, the invention **10** seeks the provision of a thermostatic device capable of opening or closing the terminals of an electric circuit, as the temperature rises and falls.

A further purpose of the invention is the **15** provision of a thermostatic device operated by the expansion and contraction of mercury when the latter is inclosed in a container in connection with the circuit closing medium, the latter operating in the container as the mercury expands or contracts, **20** since it is carried above and on top of the mercury.

Further purposes of the invention appear **25** hereinafter as it is set forth in detail.

25 To the exact construction in which it is shown and described, the invention is not to be restricted. The right is reserved to make such changes or alterations as the actual reduction to practice may suggest, in so far as **30** such changes or alterations are comprehended in spirit by the annexed claims.

In the accompanying drawings:

Figure 1 is a view in side elevation of the improved switch;

35 Fig. 2 is a longitudinal sectional view through the same.

Referring to the drawings, there is shown a back 1 on which the whole mechanism is mounted, this back being made of some **40** insulating material preferably hard wood, so that it may be attached to a wall or other place where it is desired to mount the improved switch.

Mounted upon the back 1 there is a glass **45** tube 2 which is held on the back by suitable strap members 3, the globe terminating at the bottom in the bowl 4 and being provided with an open top which is closed by a detachable cap 5, packing 6 being inserted **50** between the cap and the tube so that the latter may be held tight when the cap is attached.

In the lower end of the tube 2 there is contained a quantity of mercury 7 which

rises and falls in the tube as the temperature **55** of the place wherein the device is used rises and falls. The tube for a specified portion of its height is provided with the graduations representative of the degrees of temperature indicating the heat necessary to raise the mercury to the height of a particular graduation.

Slidably mounted within the tube 2 and on top of the mercury there is a composite rod member 9 of reduced cross section as **65** compared to the cross section of the tube. This rod member 9 is formed with a disk foot 10, cupped as indicated by 11 on the under face and it is this cupped portion of the foot which rests on top of the mercury. The rod 9 terminates at the top in a disk head 12 and this latter and the foot are of such a diameter that they may slide freely within the tube 2. The head 12, foot 10 and the portions of the rod adjoining **70** these two parts are made of suitable insulating material, preferably hard rubber, but the intermediate portion 13, of the rod, while of the same diameter as the remainder, is made of some conducting material preferably **75** hard drawn copper or silica bronze. This intermediate portion 13 is formed of reduced threaded ends which screw into the hard rubber portions of the rod.

In order to keep the rod member in its **85** lowermost position when not raised by the expansion of the mercury, a spiral spring 14 is provided and this spiral spring is compressed between the cap 5 and the head 12.

90 The construction which provides for the reduction in the diameter of the composite rod between the head and the foot will permit variations in diameter of the latter due to temperature changes without imposing **95** any resistance to the successful operation of the rod due to frictional contact with the sides of the tube 2. Also, it provides for the contact springs being hermetically sealed in the wall of the tube 2 and projecting into **100** the tube and bearing upon the rod and being permitted to yield because of the fact that there is a space between the reduced portion of the rod and the side walls of the tube. Yielding of the springs would not be possible were the rod uniformly of the same **105** diameter throughout its length as the head and foot and with no provision made for the

yielding of the contact springs, variations in the diameter of the rod due to temperature changes would interfere with effectual contact with the contact springs.

- 5 Hermetically sealed in the opposite sides of the tube 2 so that their ends may yieldably bear upon opposite sides of the rod 9 there are contact springs 15, these springs being connected to binding posts 16 by suitable connecting rods 17, the binding posts 16 are mounted on the back 1 and the connecting rods connect them with the contact springs 15 on those ends which project through the walls of the tube 2. At specified 10 points above the binding posts 16 there are second binding posts 18 connected to the contact springs 19 which are identical with the contact spring 15 and mounted in the same way, the manner of connecting the binding posts 18 with their contact springs being identical with the manner of connecting the binding posts 16 with their contact springs 15. In practice the binding posts 16 and 18 are connected with the terminals of different 15 relays the former throwing heating devices in and out of circuit and the latter for throwing cooling devices in and out of circuit as the mercury rises and falls.

In the construction of the device the distance between the heads 10 and 12 is designed to equal twice the distance from the high graduation to the graduation at which the heating devices are intended to operate. The length of the lower section 9 of the rod, 20 is equal to the distance between the designations 40 and 110. The upper section is equal to the distance from the graduation from which the heating devices operate to the graduation at which the cooling devices 25 operate.

The distance from the top of the head 12 to the upper end of the tube is equal to the distance of the section 9 plus a reasonable space for the spring, so in case the mercury 30 rises to the maximum temperature there will still be a space left for the latter.

Suppose the maximum temperature is 110 degrees and the temperature at which the cooling devices are intended to operate is 60 degrees, and the temperature at which the heating devices operate is 40 degrees. Then the total distance between the heads 10 and 12, not including them, is twice the distance between the 110 degrees and the 40 degrees 35 graduation. The length of the lower section

9, as before said, is equal to the distance between 110 degrees and 40 degrees. The length of the metallic section is therefore equal to the rest.

The distance from the top of the head 12 to the top end of the tube must be equal to the distance between 40 degrees and 110 degrees graduations plus a reasonable space for the spring so that in case the mercury rises to 110 degrees and consequently the head 12 forced through the distance equal to the 110 and 40 degrees graduation, and will still be a space left for the spring.

Then the lower contact springs must be in such a position as to be just touching the metallic rod when the mercury is at 40 degrees, so that when the temperature drops to 40 degrees, the connection of the lower springs will be closed and the heating devices thrown into circuit but as soon as the temperature rises over 40 degrees by the heat given off from said devices, the rod will be forced up and thus the connections broken, as a result throwing the heating devices out of circuit.

The upper springs are so placed as to be just touching the metallic rod when the mercury reaches 60 degrees, so that in summer time as soon as the mercury rises to 60 degrees, the cooling devices will be thrown into circuit and as soon as it drops lower than 60 degrees, the contact will be broken and the devices thrown out of circuit.

The invention having been described what is claimed as new and useful is:

A device for the purpose indicated comprising a tubular container, a column of mercury carried in the bottom of the container, a composite rod member slidably mounted in the container and formed both with a head and a foot approximating the internal cross sectional area of the container but having its body portion considerably reduced in cross sectional area, the foot bearing on the column of mercury, the head and foot and reduced portion of the rod being of insulating material but the reduced portion containing a section of conducting material, contact springs set in opposite sides of the container and bearing upon the reduced portion of the rod, and a spring within the container and compressed between the top of the latter and the head of the rod.

In testimony whereof I affix my signature.

JOHN RIOS.
